CLAIM

The ornamental design for a mount for kitchen appliance as shown and described.

DESCRIPTION

FIG. 1 is a top front perspective view of a mount for kitchen appliance, showing my design;

FIG. 2 is a top view thereof;

FIG. 3 is a bottom view thereof;

FIG. 4 is a front view thereof;

FIG. 5 is a rear view thereof;

FIG. 6 is a right-side view thereof;

FIG. 7 is a left-side view thereof; and,

FIG. 8 is a perspective view thereof, shown in a condition of use.

The features shown in broken lines and the area within the broken lines show environmental structure only and form no part of the claimed design.
